US00D702693S

(12) **United States Design Patent**
Gallagher et al.

(10) **Patent No.:** **US D702,693 S**
(b4) **Date of Patent:** **** Apr. 15, 2014**

(54) **DIGITAL STORAGE MEDIUM CARD**

(75) Inventors: **Timothy Gallagher**, Christchurch (NZ);
Kerry Jackson Tahawai Bird, Maketu (NZ)

(73) Assignee: **Digital Hard Copy**, New York, NY (US)

(**) Term: **14 Years**

(21) Appl. No.: **29/407,209**

(22) Filed: **Nov. 23, 2011**

(51) **LOC (10) Cl.** **14-02**

(52) **U.S. Cl.**

USPC **D14/436**

(58) **Field of Classification Search**

(57) **CLAIM**

We claim the ornamental design for a digital storage medium card, as shown and described.

DESCRIPTION

FIG. 1 is a bottom perspective view of a digital storage medium card showing the new design;

FIG. 2 is a top perspective view thereof;

FIG. 3 is a front elevational view thereof;

FIG. 4 is a rear elevational view thereof;

FIG. 5 is a side elevational view thereof;

FIG. 6 is another side elevational view thereof;

FIG. 7 is a bottom view thereof; and,

FIG. 8 is a top view thereof.

Broken lines and portions contained within broken lines, are not claimed.

1 Claim, 6 Drawing Sheets
